Specification of Letters Patent. Patented Apr. 27, 1920.

Application filed September 26, 1912. Serial No. 722,887.

To all whom it may concern:

Be it known that we, FRANK E. DAVIS and DAVID A. BIEBINGER, both residents of La Crosse, in the county of La Crosse and State of Wisconsin, have invented new and useful Improvements in Plows, of which the following is a full, clear, and exact description.

The invention relates to plows, and more particularly to that type of plow which is commonly known as frameless and in which draft-operated lifting-mechanism is provided.

The invention designs to provide, improved draft-operated mechanism for lifting the plows, improved controlling-mechanism for said lifting-mechanism and improved adjustable connections whereby the plows may be adjusted to work at different depths. The invention further designs to provide an improved gang-plow, and to provide a plow of improved construction.

The invention consists in the several novel features hereinafter set forth and more particularly defined by claims at the conclusion hereof.

In the drawings: Figure 1 is a plan of a plow embodying the invention. Fig. 2 is a side elevation, the land-wheel being removed, parts being shown in section, the plows being shown in raised position for transportation. Fig. 3 is a similar view, the plow being shown in position assumed when the plow is lowered into the soil. Fig. 4 is a transverse section taken on line 4—4 of Fig. 2. Fig. 5 is a section taken on line 5—5 of Fig. 1. Fig. 6 is a detail of the draft-operated lifting-mechanism in its inoperative position, the plows being raised. Fig. 6^a is a similar view showing the parts in position assumed when the plows have been lowered. Fig. 6^b is a view of the same showing the dog of the draft-operated lifting-mechanism shifted into operative position. Fig. 6^c is a view of the same showing the parts in position assumed when the dog has been released from the ratchet and before the controlling mechanism has been restored to its normal lock position. Fig. 7 is a plan of the same. Fig. 8 is a view partly in plan and partly in section, showing the locking devices in position assumed while the bearing and releasing-bar for the lever-lock which holds the plow is operative, as occurs

during the operation of the draft-operated lifting-mechanism until the plows have been raised to the point where they are to be locked. Fig. 9 is a similar view showing the lock in operative position and the releasing and holding bar in inoperative position.

A plow - carrying structure comprises beams 13, which are rigidly secured together in spaced relation at their front ends by brackets 14, 15 and a cross bar 16 and at their rear ends by brackets 17. A plowshare 12 is rigidly secured to each beam 13. The plow illustrated in the drawings comprises a gang of three plows, but it will be understood that any desired number of plows may be employed.

The front end of this plow-carrying-structure is adjustably sustained by two crank axles 23 and 24 which are adapted to serve as lifting connections for the sides of the structure respectively. Axle 23 is pivoted in the furrow-wheel 25, and is connected to the plow-supporting structure to adjust the plows carried by the structure relative to the ground, by swinging the axle about its axis in the furrow-wheel. Axle 24 is pivoted in the land wheel 26 and is also pivotally connected to the plow-supporting structure. These crank-axles 23 and 24 which are journaled in brackets 27, 28 and 29 which are respectively secured to the plow beams 13, 85 each extends transversely across the plow-carrying structure.

The rear end of this structure is sustained by a standard 18 which has a runner 19 at its lower end adapted to travel on the ground, the standard being slidably held in a sleeve 20 which is rigidly secured to one of the plow-beams 13 by bars 21 and 22. The rear end of the plow may be adjusted relatively to the ground, by a lever 30 which is pivoted to one of the bars 22 and is connected to a standard 18 by a link 31, a stop 32 for lever 30 being provided on one of the bars 21 when it is in one of its alternative positions. Link 31 has its upper end pivoted to a collar 33 which is held on standard 18 by pins above and below the collar respectively. The purpose in providing this adjustment, is to permit the rear of the plow to be raised entirely clear of the ground when the plow is not in use. When lever 30 is in the position shown in Fig. 2, the relation

of the pivotal connections of the lever and link will be such that the sleeve 20 will be held in raised position automatically by this connection. A power mechanism is provided for shifting the crank axles to raise both sides of the plow-carrying structure. This mechanism is operable from the land wheel 26 which serves as a traction-wheel for driving this mechanism. A sprocket-wheel 35 is suitably secured to the hub of the land wheel which is mounted on the inturned spindle 36 of arch axle 24. A collar 37 on said spindle, holds the land wheel and sprocket on the spindle. This sprocket serves to drive a chain 38 which extends around a sprocket wheel 39 which is loose on crank-axle 24 and has integrally formed therewith a clutch or ratchet-wheel 40 which will be constantly driven when the plow is in operation. These sprockets and chain serve as power-mechanism for shifting the crank-axles to raise the plows. A tightener 41 for chain 38 is mounted on an arm 42 which is secured to shaft 24.

25 Wheel 40 is adapted to operate a dog 43 which is pivoted as at 44 to a collar or carrier 45 which is pivoted on shaft 24. Said collar or carrier is connected by a link 46 to an arm 47 which is rigidly secured to the 30 axle 23 which is carried by the furrow-wheel 25. As a result, when dog 43 is shifted into engagement with ratchet 40, the latter, which is constantly driven by the rotation of the land-wheel, as the plow is pulled, will operate carrier 45 around axle 24 to shift link 46 which will operate arm 47 to rock axle 23, and thus raise and lower the front end of the plow-supporting structure. Rotation of axle 24 about its axis in 35 wheel 26, will cause the front end of the plow-carrying-structure to be raised or lowered according to the direction in which the axle is operated.

Axle 24 is connected to be operated by 40 axle 23, by an adjustable connection between said axles which serves as adjusting-mechanism for the land-wheel relatively to the furrow-wheel. This connection comprises a segmental rack 49 which is rigidly secured 45 to axle 23, a lever 50 which is pivoted on said shaft and adapted to be locked to said segment in different positions by a spring-pressed bolt 51 which is releasable by a finger-lever 52 on lever 50, and arm 53 which is rigidly secured to shaft 24 and a link 54 between said arm and lever 50. By means of this connection between said axles, the power-operated lifting-mechanism will rock axle 23 by means of dog 43, collar 45, link 46 and arm 47, and axle 24 will be simultaneously rocked by means of segment 49, lever 50 and link 54 and arm 53, so that both of the arch-axles will be operated by power to raise both sides of the plow-supporting structure and the plows carried

thereby, out of the ground. By adjusting lever 50 along rack 49, axle 24 will be rocked to raise or lower the land-wheel relatively to the furrow-wheel. A spring 55 connected to lever 50 and rack 49 holds the rack in 70 yielding but connected relation to the lever during adjustment of the lever.

Oppositely extending arms 56 and 57 are secured to shaft 23 and counter-balance springs 58 and 59 are applied to said arms 75 to aid in lifting, and to cushion the lowering operations.

The mechanism for controlling dog 43 to render the draft-operated lifting-mechanism operative and inoperative comprises 80 a slotted cam 60 which has its front end pivoted to one of the bearings 27 as at 61, and its opposite end connected by a link 62 to an arm 63 on a controller-shaft 64. A segmental slot 65 in cam 60 is formed to 85 guide stud 66 on dog 43 which rides in said slot, and when the dog is shifted by movement of the cam about its pivot 61, with the dog in its lowered position, the dog will be shifted into engagement with ratchet 40 and 90 will remain in engagement therewith until stud 66 is operated to disengage the dog by cam-surface 67 on the upper end of slot 65. Controller-shaft 64 has an arm 68 which is connected by a link 69 to a slidable lock-holding and releasing-bar 70 on a forwardly extending lowering-lever 71, which is fulcrumed at 71^a. Link 69 may be operated to 95 operate controller-shaft 64 by a rod 72 which is connected to link 69 and to a controller-lever 73 which is pivoted to the front end of lever 71, as at 74. Link 69 is also operatively connected to the releasing bar 70 by rod 72. When the plows are lowered in the soil and it is desired to raise them by 100 the draft-operated mechanism, the operator will push the lower end of lever 73 backwardly which will pull rod 72 forwardly and cause link 69 to rock shaft 64 so that arm 63 on said shaft will operate link 62 110 to swing cam 60 into position to cause dog 43 to pass into engagement with the rotating ratchet 40.

Lever 71 is provided to lower the plows manually and raise them if so desired, and 115 is adapted to be locked to a rack 75 which is secured rigidly to one of the plow beams, by a spring-pressed bolt 76. When lever 71 is locked to rack 75 both of the axles 23, 24, will be locked against rotation and will thus 120 secure the plow-carrying structure.

Lever 71 is connected to operate axle 23 by a link 87 which is pivoted to said lever at 88 and to an arm 89 integral with segment 49. A finger-lever 90 on lever 71 is 125 connected to bolt 76 by a rod 91 so that the lever 71 can be released from segment 75 and then operated to operate axles 23, 24 to raise or lower the plow-supporting structure. When the plows are in raised posi- 130

tion, as shown in Fig. 2, and it is desired to lower them, it is only necessary to operate finger lever 90 to release bolt 76, whereupon lever 71 and the raising and lowering connections will be free to permit the weight of the plows to lower them or, if necessary, pressure may be applied to lever 71. It will be observed that the link 87, aside from serving as an operative connection for manually operating shaft 23 to raise or lower the plows, serves, when lever 71 is locked, to lock axle 23 against rotation and also axle 24 because it is locked to axle 23. When lever 73 is shifted to operate the controlling-mechanism for the power-lifting-mechanism, rod 72 will also operate bar 70 which is slidably mounted on lever 71 and is extended into position to release bolt 76 at the time that the power-lifting mechanism is rendered operative. When bar 70 is thus shifted, a hole 80 therein will be brought into position to permit a laterally sliding spring-pressed bolt 81 to pass into said hole and lock said bar 70 into position to hold bolt 76 released, until bolt 81 is withdrawn from engagement with bar 70 by an inclined releasing cam 84 which is fixed to one of the plow beams and is formed to withdraw bolt 81 from bar 70 when the plow has been raised. During the lifting-operation, bolt 81 holds bar 70 to release bolt 76 from rack 75, and at the end of such an operation, bolt 81 will release bar 70 to permit a spring 85 applied to bolt 76 to force said bolt into notch 75^a of segment 75 and lock the arch-axes in raised positions. Bolt 76 when shifted by lever 90, will not be held in released position by and will be independent of bar 70, because the latter will become operative only when controller-lever 73 is operated to render the draft-operated lifting-mechanism operative.

The operation of the improved plow is as follows: assuming the parts to be in position shown in Fig. 2, at which time the plows will be elevated or raised out of the ground, and it is desired to lower the plows, lever 30 will be swung into position indicated in Fig. 3 to raise the runner 19 above the ground, so that the plows will be free to be raised and lowered without interference from the runner. This lever 30 may be left in this position during the operation of the plow in the field and is usually rendered operative only when the plow is being transported. To lower the plow, the operator will press finger-lever 90 toward the handle of lever 71 to cause rod 91 to operate lock-bolt 76 against the force of spring 85, and to withdraw the bolt from the notch 75^a in rack 75. This unlocking of bolt 76 occurs independently of the controlling-mechanism for the draft-operated lifting-mechanism. The weight of the plows will cause the arch-axes to swing in the carrying-wheels respectively, under control of lever 71. The latter lever swinging about its fulcrum 71^a will control the oscillation of the arch-axes 23, 24 by means of link 87, arm 89, segment 49, lever 50, link 54, and arm 53. Upon release of finger-lever 90, when the plows have been lowered, lock-bolt 76 will pass into one of the notches 75^b in rack 75 and will lock lever 71 and its connections, so that both of the arch-axes will be locked against oscillation. If necessary, lever 50 may be adjusted relatively to rack 49, to give the plows and furrowwheel the desired depth in the soil relatively to the land. By adjusting lever 71 in the different notches of rack 75, the depth of the plows may also be varied.

When plowing, the parts will be in position shown in Fig. 3 of the drawings. When it is desired to raise the plows out of the ground, the operator will push the lower end of controller lever 73 backwardly, which will cause rod 72 which is connected to controller-shaft 64 by means of arm 68 and link 69, to rock said shaft and also operate bar 70. The operation of bar 70 will release bolt 76 from rack 75 and thus release the lever 71 and the connections for locking the structure in lowered position. Shaft 64 will also rock arm 63 and operate link 62 to cause slotted guide 60 to shift stud 66, so that dog 43 will pass into operative engagement with the ratchet 40. The latter will rotate and operate dog 43 until stud 66 passes into the upper portion of slot 65 when it will be withdrawn from the ratchet. A slot 62^a is formed in cam 60 to provide a loose connection for link 62 to cause bar 70 to release lever 71 and its connections before the draft-operated lifting-mechanism is rendered operative. When dog 43 is operated by ratchet 40, it will rock arm 45 on axle 24, the arm will operate link 46 and arm 47 which is fixed on axle 23, oscillation of axle 23 will operate rack 49, lever 50, link 54, arm 53 and axle 24 so that both of the crank-axes will be rocked upwardly about the carrying-wheels. When bar 70 has been operated by controller-lever 73 and has released lock-bolt 76, bolt 81 will pass into hole 80 in said bar and lock this holding and releasing bar in position to keep bolt 76 released from rack 75 until the cam 84 of the plow-carrying structure engages bolt 81 and withdraws it from bar 70. This release occurs when the bolt 76 reaches the notch 75^a which is adapted to lock the lever in position assumed when the plows are raised. During the lowering of the plows, the controlling-mechanism, including shaft 64, link 69, link 62 and cam 60, remain in normal relation so that the releasing and holding bar 70 will not be operated to release the lock-bolt 76. When bolt 81 is withdrawn from hole 80, in bar 71, by cam 84, spring 85 in forcing bolt 76 into the notch 75^a, will

act upon bar 70 to restore the controlling mechanism to its normal position and then it will be in readiness for a subsequent operation.

5 The operating mechanism for the lifting connections exemplifies one in which power is taken from one of the carrying wheels and first transmitted to the lifting connection for the other carrying wheel and then transmitted by a cross-connection between the lifting connections to the lifting connection for the power wheel.

10 The invention also exemplifies one in which the power wheel rotates relatively to its lifting connection and in which the wheel, as it rolls over the ground, operates the connection without being rigid therewith.

15 In the operation of the connection between the shafts 23 and 24 of the crank connections, the inner portion of lever 50 between the lock 51 and crank-axle 23 operates as an adjustable arm by which the relative position of the two lifting connections may be adjusted.

20 25 The invention set forth is of that type in which the plowshare is rigid with a carrying-structure which comprises members or beams fixedly secured together in spaced relation and which is directly supported by lifting connections between the sides of the frame and the land wheel at one side and a furrow wheel at the other side and the invention exemplifies a plow of that type in which the lifting connections for the sides 30 35 of the frame are connected together by suitable means so that the power lift mechanism will operate both of the lifting connections through the connecting means to simultaneously raise both sides of the frame.

40 45 It will be observed that the crank axles are shifted differentially by the power operated means and as a result the bottoms of the plow bodies are kept in substantially horizontal alinement, both when the plows are lowered and when they are raised, the differential movement serving to compensate for the additional movement necessary to bring the wheels which are at different elevations when plowing to the same elevation 50 relatively to the frame when the plows are raised.

55 The invention is not to be understood, as restricted to the details set forth, since these may be modified by the skilled mechanic within the scope of the appended claims without departing from the spirit and scope of the invention.

60 Having thus described the invention, what I claim as new and desire to secure by Letters Patent is:

1. In a frameless plow, the combination with a frame structure having one or more plowshares rigidly secured thereto, and ground wheels at the sides of the structure 65 respectively, of pivotal lifting connections

between the wheels and the structure respectively, operable to raise both sides of the structure and whereby said wheels will be held to support both sides of the structure when the plows are raised and when they are lowered, a power mechanism operated by one of said wheels, means operable by said mechanism for simultaneously shifting both of the lifting connections to raise both sides of the structure, and means for controlling the operation of said means by the power mechanism, said power wheel being rotated relatively to the lifting connections during the lifting operation.

2. In a frameless plow, the combination with a frame structure having one or more plowshares rigidly secured thereto, and ground wheels at the sides of the structure respectively, of lifting connections between the structure and the wheels respectively, operable to raise both sides of the structure and whereby said wheels will be held to support both sides of the structure when the plows are raised and when they are lowered, a power mechanism operated by one of said wheels, means operable by the power mechanism for shifting both of said connections, including an adjusting lever whereby the relative position of one of the wheels with respect to the other may be varied, and means for controlling the operation of said means by the power mechanism, said power wheel being rotated relatively to the lifting connections during the lifting operation.

3. In a frameless plow, the combination with a frame structure having one or more plowshares rigidly secured thereto and ground wheels at the sides of the structure respectively, of lifting-connections between the wheels and the structure respectively, operable to raise both sides of the structure and whereby said wheels will be held to support both sides of the structure when the plows are raised and when they are lowered, a power mechanism operated by one of said wheels, means operable by said mechanism for shifting both of the lifting connections to raise both sides of the structure, means to automatically lock both lifting connections at the end of a lifting operation, and means for controlling the operation of said means by the power mechanism, said power wheel being rotated relatively to the lifting connections during the lifting operation.

4. In a frameless plow, the combination with a frame structure having one or more plowshares rigidly secured thereto, and ground wheels at the sides of the structure respectively, of crank-connections between the structure and the wheels respectively, operable to raise the sides of the structure and whereby the wheels will be held to support both sides of the structure when the plows are raised and when they are lowered, a power mechanism operated by one of said

wheels, means operable by the power mechanism for shifting both of the crank-connections simultaneously to raise both sides of the structure, and means for controlling the 5 operation of said means by the power mechanism, said power mechanism being rotated relatively to one of the lifting connections during a lifting operation.

6. In a frameless plow, the combination 10 with a frame structure having one or more plowshares rigidly secured thereto and ground-wheels at the sides of the structure respectively, of crank-connections between the structure and the wheels respectively, 15 operable to raise the sides of the structure and whereby the wheels will be held to support both sides of the structure when the plows are raised and when they are lowered, a power mechanism operated by one of said 20 wheels, means operable by the power mechanism for shifting both of the crank-connections to simultaneously raise both sides of the structure, means to automatically lock both crank-connections at the end of a lifting operation, and means for controlling the 25 operation of said means by the power mechanism, said power mechanism being rotated relatively to one of the lifting connections during a lifting operation.

7. In a frameless plow, the combination 30 with a frame structure having one or more plowshares rigidly secured thereto and ground wheels at the sides of the structure respectively, of crank-connections between the structure and the wheels respectively, 35 operable to raise the sides of the structure and whereby the wheels will be held to support both sides of the structure when the plows are raised and when they are lowered, a power mechanism operated by one of said 40 wheels, means operable by the power mechanism, for shifting both of said crank-connections, comprising an adjusting lever whereby the relative position of one of the 45 wheels with respect to the other may be varied, and means for controlling the operation of said means by the power mechanism, said power mechanism being rotated relatively to one of the lifting connections 50 during a lifting operation.

8. In a frameless plow, the combination 55 with a frame structure having one or more plowshares rigidly secured thereto and ground wheels at the sides of the structure respectively, of crank connections between the structure and wheels respectively, operable to lift the sides of the structure and whereby the wheels will be held to support the structure when the plows are raised and 60 when they are lowered, an element rotating with one of said wheels and at the lower end of one of the crank connections, and means operable by said element for shifting both of the crank connections simultaneously to raise both sides of the structure,

comprising a clutch above said rotating element and driven thereby, and operating means between the clutch and said crank connections.

9. In a frameless plow, the combination 70 with a frame structure having one or more plowshares rigidly secured thereto and ground wheels at the sides of the structure respectively, of crank connections between the structure and wheels respectively, operable to lift the sides of the structure and whereby the wheels will be held to support the structure when the plows are raised and when they are lowered, an element rotating 75 with one of said wheels and at the lower end of one of the crank connections, and means operable by said element for shifting both of the crank connections simultaneously to raise both sides of the structure, comprising a clutch above said rotating element and driven thereby, and operating means between the clutch and said crank connections, including an adjusting lever between said connections.

10. In a frameless plow, the combination 90 with a frame structure having one or more plowshares rigidly secured thereto, and ground wheels at the sides of the structure respectively, of pivotal lifting connections between the wheels and the structure respectively, operable to raise both sides of the structure and whereby the wheels will be held to support the structure when the plows are raised and when they are lowered, a power mechanism operated by one of 95 said wheels, means operable by said mechanism for conjointly shifting the lifting connections to raise both sides of the structure and to shift the axis of one of the wheels relatively to the axis of the other 100 wheel, and means for controlling the operation of said means by the power mechanism.

11. In a frameless plow, the combination 110 with a frame structure, plowshares rigidly secured thereto, and ground wheels at the sides of the structure respectively, of crank-connections between the structure and the wheels respectively, operable to raise the sides of the structure and whereby the wheels will be held to support the structure 115 when the plows are raised and when they are lowered, a power mechanism operated by one of said wheels, means operable by the power mechanism for conjointly shifting the crank-connections to raise both sides of the structure and to shift the axis of one of the 120 wheels relatively to the axis of the other wheel, and means for controlling the operation of said means by the power mechanism.

12. In a frameless plow, the combination 125 of a frame structure having one or more plowshares rigidly secured thereto, and ground wheels at the sides of the structure respectively, of crank-axles between the

structure and the wheels respectively, operable to raise both sides of the structure, and whereby the wheels will be held to support the structure when the plows are raised 5 and when they are lowered, a power mechanism operated by one of said wheels, means for conjointly shifting the lifting connections from said power lift mechanism to raise both sides of the structure and to shift 10 the axis of one of the wheels relatively to the axis of the other wheel, and means for controlling the operation of said means by the power mechanism.

12. In a plow, the combination of a plow-carrying structure, carrying-wheels at the 15 sides thereof respectively, a crank-axle for one of said wheels, and draft-operated lifting-mechanism for the structure comprising a pair of sprocket wheels and a chain there- 20 between.

13. In a plow, the combination of a plow-carrying structure, carrying-wheels at the sides thereof respectively, a crank-axle for one of said wheels, and draft-operated lifting-mechanism for the structure comprising 25 a sprocket-wheel secured to rotate with one of the carrying-wheels, another sprocket-wheel on the crank-axle, and a chain between said sprocket-wheels, said axle being pivoted to said structure.

14. In a plow, the combination of a plow-carrying structure, carrying-wheels at the sides thereof, a crank-axle for each of said 30 wheels, each pivotally connected to the structure, draft-operated lifting-mechanism comprising a pair of sprocket-wheels and a chain-connection between them, and means for operating both of said axles by the draft-operated lifting-mechanism.

40 15. In a plow, the combination of a plow-carrying structure, carrying-wheels at the sides thereof respectively, crank-axles for said wheels pivoted to the structure at eccentric points, mechanism for the structure comprising a pair of sprocket-wheels and a chain connection therebetween, and an operating-connection between said axles.

16. In a plow, the combination of a plow-carrying structure, carrying-wheels at the 50 sides thereof respectively, crank-axles for said wheels respectively, pivoted to the structure, at relatively eccentric points, draft-operated lifting-mechanism, and a connection for operating one of said axles 55 from the other, said mechanism comprising a pair of sprocket-wheels and a chain between them.

17. In a plow, the combination of land and furrow wheels, a structure having one 60 or more plows rigidly secured thereon, crank axles having their lower ends pivoted in said wheels and having their upper ends extended inwardly and pivoted to the structure respectively, and operable to lift the 65 structure by swinging movement, draft-

operated mechanism operated by one of said wheels comprising a wheel mounted on and liftable with the structure, and means operable by said mechanism for simultaneously shifting both of the crank-axles about the axes of said wheels to lift both sides of the structure.

18. In a plow, the combination of land and furrow-wheels, a structure having one or more plows rigidly secured thereon, 70 crank-axles having their lower ends pivoted in said wheels and having their upper ends extended inwardly and pivoted to the structure, respectively, and operable to lift the structure by swinging movement about the 80 axes of the wheels respectively, draft-operated mechanism operated by one of said wheels comprising a wheel mounted on and shiftable with the structure, and means operable by said mechanism for simultaneously 85 shifting both of the crank-axles to lift both sides of the structure, the inwardly extending upper end of one crank axle being disposed in front of the other.

19. In a plow, the combination of land and furrow wheels, a structure having one or more plows rigidly secured thereon, 90 crank-axles having their lower ends pivoted in said wheels and having their upper ends extended inwardly and pivoted to the structure, respectively, and operable to lift the structure by swinging movement, draft-operated mechanism operated by one of said 95 wheels comprising a wheel mounted on and liftable with the structure, means operable by said mechanism for simultaneously shifting both of the crank-axles to lift both sides of the structure, and a lever for manually 100 shifting both of the crank-axles.

20. In a plow, the combination of land and furrow wheels, a structure having one or more plows rigidly secured thereon, 105 crank-axles having their lower ends pivoted in said wheels and having their upper ends extended inwardly and pivoted to the structure, respectively, and operable to lift the structure by swinging movement, draft-operated mechanism operated by one of said 110 wheels comprising a wheel mounted on and liftable with the structure, means operable by said mechanism for simultaneously shifting both of the crank-axles to lift both sides of the structure, a forwardly extending lowering-lever pivoted to the structure, a lock 115 for securing the lever to secure the structure, controlling-mechanism for the axle-shifting means, means for releasing and holding the lock during a lifting operation by the draft operated mechanism, operated by the controlling mechanism, and means 120 on the structure for releasing the holding means to render the lock operative when the structure has been raised by the lifting mechanism.

21. In a plow, the combination of land

and furrow wheels, a structure having one or more plows rigidly secured thereon, crank-axes having their lower ends pivoted in said wheels and having their upper ends extended inwardly and pivotally connected to the structure, respectively, and operable to lift the structure by swinging movement, draft-operated mechanism operated by one of said wheels comprising a wheel mounted on and liftable with the structure, means operable by said mechanism for simultaneously shifting both of the crank-axes to lift both sides of the structure, a forwardly extending lowering lever pivoted to the structure, a lock for securing the lever to secure the structure, controlling-mechanism for the axle shifting means, means for releasing and holding the lock during the operation of the draft operated lifting mechanism by the controlling mechanism, means on the structure for releasing the holding means to render the lock operative when the structure has been raised by the lifting-mechanism, and means for releasing the lock independently of the holding means when the structure is to be lowered by the lowering lever.

22. In a plow, the combination of a plow-carrying structure, land and furrow wheels at the sides thereof respectively, draft-operated lifting-mechanism for said structure, a lowering-lever for the structure, a lock for securing the lever to secure the structure, controlling-mechanism for the lifting-mechanism comprising a lever, a slideable bar on the lowering lever for releasing and holding the lock during the operation of the draft-operated lifting-mechanism, connected to the controller-lever, a lock for securing said bar, and a cam for operating the latter lock to release the bar.

23. In a plow, the combination of a plow-carrying structure, land and furrow wheels at the sides thereof respectively, draft-operated lifting-mechanism for said structure, a lowering-lever for the structure, a lock for securing the lever to secure the structure, controlling-mechanism for the lifting-mechanism comprising a lever, a slideable bar on the lowering lever for releasing and holding the lock during the operation of the draft-operated lifting-mechanism, connected to the controller lever, a lock for securing said bar, and a cam on the structure for operating the latter lock to release the bar.

24. In a plow, the combination of a plow-carrying structure, land and furrow wheels at the sides thereof respectively, crank-axes for said wheels respectively, draft-operated lifting-mechanism for said structure, a lowering-lever for the structure, a lock for securing the lever to secure the structure, controlling-mechanism for the lifting-mechanism comprising a lever, a slideable bar on the lowering lever for re-

leasing and holding the lock during the operation of the draft-operated lifting-mechanism, connected to the controller lever, a lock for securing said bar, and a cam on the structure for operating the latter lock to release the bar.

25. In a plow, the combination of a plow-carrying structure, land and furrow wheels at the sides thereof respectively, draft-operated lifting-mechanism for said structure, a lowering-lever for the structure, a lock for securing the lowering lever to secure the structure, controlling-mechanism for the lifting-mechanism comprising a lever, a slideable bar on the lowering lever for releasing and holding the lock during the operation of the draft-operated lifting-mechanism, connected to the controller-lever, a lock for securing said bar, a cam for operating the latter lock to release the bar, and means for releasing the lowering-lever lock without rendering said holding-means operative when the structure is to be lowered by the lowering lever.

26. In a plow, the combination of a plow-carrying structure, land and furrow-wheels at the sides thereof respectively, draft-operated lifting-mechanism for said structure, a lowering-lever for the structure, a lock for securing the lever to secure the structure, controlling-mechanism for the lifting-mechanism comprising a lever, a slideable bar on the lowering lever for releasing and holding the lock during the operation of the draft-operated lifting-mechanism, connected to the controller lever, a lock for securing said bar, a cam on the structure for operating the latter lock to release the bar, and means for releasing the lowering-lever lock without rendering said holding means operative when the structure is to be lowered by the lowering lever.

27. In a plow, the combination of a plow-carrying structure, land and furrow wheels at the sides thereof respectively, crank-axes for the wheels respectively, draft-operated lifting-mechanism for said structure, a lowering-lever for the structure, a lock for securing the lever to secure the structure, controlling-mechanism for the lifting-mechanism comprising a lever, a slideable bar on the lowering lever for releasing and holding the lock during the operation of the draft-operated lifting-mechanism, connected to the controller lever, a lock for securing said bar, a cam on the structure for operating the latter lock to release the bar, and means for releasing the lowering-lever lock without rendering said holding means operative when the structure is to be lowered by the lowering lever.

28. In a gang-plow, the combination of a frame, a plow-body mounted on said frame, a ground-wheel movable vertically relative to said frame, means for moving said

ground-wheel vertically relative to the frame for lowering the plow-body into operative engagement with the ground or for raising the plow body out of operative engagement with the ground, a lever operatively connected with said ground-wheel and adapted through the medium of said connection to be swung longitudinally of the frame upon the raising and lowering movements of the plow-body, and means actuated by said lever for adjusting the vertical position of the ground-wheel relatively to the frame for regulating the depth of plowing, the arrangement being such that said lever, by the raising of the plow-body is swung forward into convenient position for the operator at the forward end of the frame and by the lowering of the plow-body is swung backward out of the way of the operator.

29. In a gang-plow, the combination of a frame, a crank-axle mounted on said frame, a supporting wheel journaled on said crank axle, a second supporting wheel adjustably mounted on said frame, an arm mounted on said crank-axle, means actuated by a stroke of said arm in one direction for moving said second supporting wheel downward relative to said frame, a clutch one member of which is continuously driven by power from said second supporting wheel, and positively acting means adapted to be actuated by an operative movement of the other member of the clutch for giving said arm a stroke in the direction for moving the second supporting wheel downward, the arrangement being such that upon the said stroke of the arm said crank axle is turned for moving said first-named supporting wheel downward simultaneously with said second supporting wheel relative to the frame.

30. In a gang-plow, the combination of a rigid frame, a plurality of plow-bodies rigidly mounted on said frame, a crank axle mounted on said frame, supporting wheels mounted on said frame, one of which supporting wheels is journaled on said crank-axle, an arm swingingly mounted relative to said frame, means positively actuated by power from one of said wheels for swinging said arm, means actuated by said arm for rocking said crank-axle to move said wheel relatively to the frame comprising an adjustable connection between said axle and said arm whereby the height to which said wheel shall be raised by power relative to the frame may be varied.

31. In a gang-plow, the combination with a structure comprising members rigidly secured together and having a plurality of plowshares rigidly secured thereto and ground-wheels at the sides of the structure respectively, of a plurality of lifting connections between the structure and the wheels respectively, operable to raise both

sides of the structure, a power device driven by one of said wheels, means for operating the lifting connection for the other wheel from said power device, and a lifting connection for the wheel which drives the power device operatively connected to and shiftable by the operating means for the other lifting connection.

32. In a gang plow, the combination with a structure comprising members rigidly secured together and having a plurality of plowshares rigidly secured thereto and ground-wheels at the sides of the structure respectively, of a plurality of lifting connections between the structure and the wheels respectively, operable to raise both sides of the structure, a power device driven by one of said wheels, means for operating the lifting connection for the other wheel from said power device, and a cross-connection between the lifting connections for operating the lifting connection for the wheel which drives the power device.

33. In a "frameless" plow, the combination with a plurality of plow-bodies, a frame-structure to which the plow-bodies are rigidly secured and ground wheels at the sides of the structure respectively, of supporting connections between the ground wheels and the sides of the structure which are adjustable to permit the structure to be raised or lowered relatively to the wheels, a rotary power-member at the lower end of one of said supporting connections operable by one of the ground wheels, and lifting mechanism for shifting the structure relatively to both of the ground wheels comprising a connection operable by said member between the rotary member and structure in addition to and movable relatively to the latter supporting connection when the structure is being shifted by power from said member.

34. In a "frameless" plow, the combination with a plurality of plow-bodies, a frame-structure to which the plow-bodies are rigidly secured and ground wheels at the sides of the structure respectively, of supporting connections between the ground wheels and the sides of the structure which are adjustable to permit the structure to be raised or lowered relatively to the wheels, a rotary power-member at the lower-end of one of said supporting connections, operable by one of the ground wheels, lifting mechanism for shifting the structure relatively to both of the ground wheels comprising a connection operable by said member between the rotary member and structure in addition to and movable relatively to the latter supporting connection when the structure is being shifted by power from said member, and means to adjust said lifting connection to vary the position of the structure.

35. In a "frameless" plow, the combina-

tion with a plurality of plow-bodies, a frame-structure to which the plow-bodies are rigidly secured and ground wheels at the sides of the structure respectively of 5 cranks between the wheels and the structure which are adjustable to permit the structure and plow-bodies thereon to be raised and lowered relatively to the ground-wheels, a rotary power member at the lower end of 10 one of said cranks, operable by one of the ground wheels, and mechanism for shifting the structure relatively to both of the ground wheels comprising a connection driven by said power member and movable 15 relatively to the latter crank while the structure is being shifted by power from said member.

36. In a "frameless" plow, the combination with a plurality of plow-bodies, a frame-structure to which the plow-bodies are rigidly secured and ground wheels at 20

the sides of the structure respectively, of cranks between the wheels and the structure which are adjustable to permit the structure and plow-bodies thereon to be raised and 25 lowered relatively to the ground wheels, a rotary power-member at the lower end of one of said cranks, operable by one of the ground wheels, mechanism for shifting the structure relatively to both of the ground 30 wheels comprising a connection driven by said power-member and movable relatively to the latter crank while the structure is being shifted by power from said member, and means to adjust the lifting connection 35 to vary the position of the structure.
